FIRE ALARM DISPATCHING MECHANISM

Joseph F. Ebert, Hollis, N. Y., and Tellef A. Terjesen, Hoboken, N. J., assignors to Signal Engineering & Manufacturing Company, New York, N. Y., a corporation of Massachusetts

Application August 23, 1934, Serial No. 741,140

4 Claims. (Cl. 185—37)

The present invention relates to fire alarms, and more particularly to the dispatching mechanism for a fire alarm box, by the operation of which a given code signal is sent to fire headquarters, or transmitted to different stations in the system.

In apparatus of this type as heretofore constructed, the dispatching mechanism of a call box is usually set in operation by a hand lever, 10 movement of the lever causing a spring to be wound, after which, upon release of the lever, the spring acting through suitable gearing actuates the dispatching mechanism to send the code by means of a rotating code wheel. In a 15 fire alarm system employing a large number of call boxes, each having a different code number, it is desirable to be able to regulate the rate of rotation of the code wheels of the several call boxes in accordance with the number of impulses 20 in the different code calls, so that the different code signals will be transmitted with substantially uniform intervals between code impulses.

According to the present invention, there is provided an improved dispatching mechanism for 25 a fire alarm box, in which the rate of rotation of the code wheel shaft may be readily adjusted to give the desired intervals between code impulses to be transmitted by a given box. In addition, the invention provides means whereby the 30 element determining the code sequence may be readily removed and another element substituted therefor in order to change the code number of a particular box, without in any way disturbing any part of the dispatching mechanism. The 35 above and other advantageous features of the invention will hereinafter more fully appear from the following description taken in connection with the accompanying drawing, in which:—

Fig. 1 is a view in elevation of a dispatching 40 mechanism embodying the invention, as seen from the code wheel side.

Fig. 2 is a view in side elevation of the parts shown in Fig. 1, as viewed from the left.

Fig. 3 is a view in elevation as seen from the 45 left of Fig. 2, with one frame plate removed.

Fig. 4 is a fragmentary view illustrating the manner of controlling the speed of the dispatching mechanism.

Fig. 5 is a fragmentary view illustrating the 50 mounting of the code wheel.

Fig. 6 shows the code wheel of Fig. 5 removed from its driving shaft.

Like reference characters refer to like parts in the different figures.

55 Referring first to Figs. 1, 2 and 3, the dispatch-

ing mechanism, shown as having been removed from the fire alarm box in which it is normally mounted, is adapted to be actuated by a hand lever 1 which is accessible from the front of the box. The lever 1 is mounted on a shaft 2, and turning of the lever in the direction of the arrow in Fig. 1 causes a toothed sector 3 on the shaft 2 to turn a pinion 4 mounted on a shaft 5. The shaft 5 also is connected to a spring 6, shown in dotted lines, within a casing 6a carried by 10 the frame plate 7, and this spring is wound by turning of the lever 1. Consequently, upon release of the lever 1 at the end of its downward movement, the tension of the spring 6 on the shaft 5 actuates the dispatching mechanism to 15 send a predetermined signal.

The shaft 5 also carries a gear 8 in mesh with a pinion 9 on a shaft 10 on which is also mounted a code wheel 11, the detailed construction of which will be hereinafter described. The code 20 wheel shaft 10 is also connected by gearing 12 to a shaft 13 on which is mounted an escapement wheel 14, the ratio of gearing 12 being such that the escapement wheel shaft 13 rotates at a considerably higher speed than the cam wheel shaft 25 10. The teeth 14a of the escapement wheel 14 are adapted to be engaged by an escapement pawl 15 mounted on a shaft 16, and the operation of the pawl 15 is such that rotation of the wheel 14 is converted into oscillatory movement of the 30 shaft 16.

As best shown in Figs. 1 and 4, the escapement 35 pawl shaft 16 extends through the frame plate 7 and is provided at its upper end with a slot 17. An arm 18 is received in this slot 17, with one end of the arm frictionally clamped by means of a set screw 19 extending through the walls of the slot 17. The other end of the arm 18 terminates in a ball portion 20 that is received in aligned 40 grooves 21 provided in opposed faces of a pair of disks 22. The disks 22 are secured together, and are freely mounted on a shaft 23, so that when the escapement pawl shaft 16 is oscillated by the wheel 14, an oscillatory movement is also 45 imparted to the disks 22 by the arm 18.

As is evident from Fig. 1, the amplitude of the oscillatory movement of the disks 22 for a given amplitude of movement of the shaft 16 is determined by the setting of the arm 18 in the slot 17. That is to say, the farther the ball portion 50 20 is displaced from the axis of the escapement pawl shaft 16, the greater will be the amplitude of the oscillatory movement of the disks 22 and vice versa. Since the disks 22 possess considerable 55 inertia, it therefore follows that the greater the

amplitude of movement of the disks 22, the greater will be the damping effect exerted by the disks on rotation of the code wheel shaft 10. Conversely, decreasing the amplitude of oscillation of the disks 22 will tend to speed up the shaft 10. Therefore, the arm 18 cooperating with the disk 22 provides means whereby the speed of the code wheel shaft 10 may be regulated. Stated another way, it has been found that with the arm 18 set to position the ball portion 20 at the ends of the grooves 21 farthest removed from the axis of the shaft 16, the shaft 10 will rotate for approximately two minutes, for one winding of the spring 6 by the lever 1. On the other hand, with the ball portion 20 located at the ends of the grooves 21 nearest the shaft 16, the shaft 10 will rotate only thirty seconds, for one winding of spring 6, with intermediate periods of rotation obtainable for different settings of the ball portion 20 in the grooves 21.

As best shown in Fig. 1, the code wheel 11 provides around its periphery a number of code determining projections 11a, and rotation of the wheel 11 causes these projections 11a to operate a pivotally mounted arm 24. The arm 24 provides a projection 25, which is disposed between a pair of contact members 26 and 27. Normally, contact tips 26a and 27a on these contact members 26 and 30 27 are in engagement as shown, but when a code projection 11a engages the arm 24, turning of the latter in a clockwise direction about its pivot 24a causes the arm projection 25 to disengage the contact tip 27a from the contact tip 26a. As 35 the projections 11a on the code wheel 11 successively engage the arm 24, an oscillatory movement is imparted to the arm 24 which results in successive engagement and disengagement of the contact members 26 and 27. This operation of the 40 contacts causes signal impulses to be transmitted through the system, in which the fire alarm box is connected, which system forms no part of the present invention. Since the number of projections 11a on the code wheel 11 will vary for different fire alarm boxes, it is possible by regulating the speed of the code wheel shaft 10, in the manner described above, to cause the signal impulses to be transmitted with the desired intervals therebetween. Obviously, the arm 18 provides means for readily obtaining such speed regulation, without in any way disturbing other portions of the dispatching mechanism.

As previously pointed out, the present invention also contemplates an improved mounting of the code wheel 11, whereby the latter may readily be removed from the shaft 10, and this mounting is best shown in Figs. 5 and 6. To this end, the wheel 11 carries a bracket 28 having an opening 29 extending therethrough for freely receiving the projecting end of the shaft 10. The bracket 28 also provides a slot 30 for receiving a pin 31 extending transversely through the shaft 10. Therefore, when the shaft 10 is passed through the opening 29 in the bracket 28 with the pin 31 received in the slot 30, the code wheel 11 is adapted to rotate with the shaft 10. After a code wheel 11 has been so positioned on the shaft, it is secured against removal therefrom by turning set screws 32 to draw together portions of the bracket on opposite sides of the slot 30, thereby causing the bracket to hold the pin 31 tightly.

When it is desired to remove the code wheel 11 and replace it with another wheel having a different code determination, it is only necessary

to loosen the screws 32 and withdraw the wheel from the shaft 10. Then when a wheel 11 having a different code determination is placed on the shaft, the pin 31 engaging with the slot 30 of the new wheel insures that the new wheel will occupy exactly the same angular position on the shaft 10 as did the wheel just removed. This insures that when code wheels are changed on the dispatching mechanism, there is no possibility of the code being mis-sent by the new wheel, owing to it being positioned on the shaft 10 in the wrong angular relation with respect to the contact operating arm 24.

From the foregoing, it is apparent that by the present invention there is provided an improved fire alarm dispatching mechanism characterized by the fact that the speed with which signal impulses are transmitted thereby may be conveniently regulated without in any way disturbing the arrangement, or functioning, of the mechanism. Furthermore, the code determining element of the mechanism can be quickly removed and a different element substituted therefor without any possibility of the substitution causing any disturbance in the timing of the mechanism, when operated.

We claim,

1. In a motor for driving a fire alarm dispatching mechanism, the combination with a rotatably mounted shaft for the purpose of carrying a code wheel and a train of gearing for driving said shaft, said gearing being operated by a spring which is wound upon actuation of the mechanism, of a shaft carrying an escapement pawl for converting rotation of one member of said gear train into oscillatory movement of said escapement shaft, a rotatably mounted damping disk and an adjustable link extending between the surface of said disk and the axis of said escapement shaft for regulating the speed of rotation of said code wheel shaft.

2. In a motor for driving a fire alarm dispatching mechanism, the combination with a rotatably mounted shaft for the purpose of carrying a code wheel and a train of gearing for driving said shaft, said gearing being operated by a spring which is wound upon actuation of the mechanism, of a shaft carrying an escapement pawl for converting rotation of one member of the gear train into oscillatory movement of the shaft, a rotatably mounted damping disk and an arm adjustably carried by said escapement shaft and having its free end loosely connected to said disk for converting oscillatory movement of said shaft into oscillatory movement of said disk, the effective length of said arm being adapted to determine the amplitude of the oscillatory movement of said disk.

3. In a speed controlling mechanism for spring motors, the combination with a spring driven train of gearing and a shaft carrying an escapement pawl for converting rotation of one member of said gear train into oscillatory movement of the escapement shaft, of a freely mounted damping disk having a slot therein, and an arm extending from said escapement shaft having its free end received in said slot, said arm being radially adjustable on said shaft, with the position of the free end of the arm in said slot determining the amount of damping effect exerted by said disk on the oscillatory movement of said escapement shaft.

4. In a speed controlling mechanism for spring motors, the combination with a spring driven

train of gearing and a shaft carrying an escapement pawl for converting rotation of one member of said gear train into oscillatory movement of the escapement shaft, of a freely mounted damping disk having a slot therein, an arm extending from said shaft having a rounded portion at its free end received in said slot, and

means for clamping said arm on said shaft with its rounded end at different distances from the axis of said shaft to vary the amplitude of oscillation of said damping disk.
